HENRY J. STUART, OF DERBY, CONNECTICUT, ASSIGNOR TO ROBERT N. BASSETT COMPANY, INCORPORATED, OF SHELTON, CONNECTICUT, A CORPORATION OF CONNECTICUT.

BUTTON-CLASP.

1,290,679.

Specification of Letters Patent.

Patented Jan. 7, 1919.

Application filed July 17, 1918. Serial No. 245,308.

To all whom it may concern:

Be it known that I, HENRY J. STUART, a citizen of the United States, residing at Derby, in the county of New Haven and State of Connecticut, have invented a certain new and useful Improvement in Button-Clasps, of which the following is a specification.

My invention relates to button clasps, but more particularly to those which are provided with a bar or support for carrying the looped extremity of the button tab, and its object is to so construct a clasp of this character that the button tab may be mounted on its supporting bar after its looped extremity has been formed.

I attain this and other objects of my invention in the device set forth in the following description and accompanying drawings in which like reference characters refer to corresponding parts.

In the drawings:

Figure 1 is a front view of my improved clasp, a part of the button tab being shown broken away;

Fig. 2, a central, vertical, sectional view taken on line α — α in Fig. 1;

Figs. 3 and 4, front and vertical sectional views showing the position of the parts during the process of assembling;

Fig. 5, a perspective view of the button tab;

Figs. 6 and 7, front and vertical sectional views of a modification, and

Fig. 8, a front view of a further modification.

Referring to Figs. 1 to 5 inclusive, the clasp consists of an attaching loop A, a button loop B and an attaching loop C which latter carries a button D. The attaching loop A is bent up out of a single piece of wire having its extremities terminating in its lower side 2, 2 and projecting downwardly in the form of flattened pintle straps 3, 3. The outside edges 4, 4 of these pintle straps are formed cam-shaped for a purpose which will hereinafter appear. The button loop B is also bent up out of a single piece of wire so that the wire extremities 5, 5 will terminate about midway of its top bar thereby forming the top side of the loop. This button loop is bent after the manner of other button loops being provided

with an enlarged opening through which the button may be passed and a restricted opening below the same which embraces and holds the shank of the button D. If desired, the upper portion of the enlarged opening may be provided with a sheet metal bridge 6. The flattened pintle straps 3, 3 are curled around the outer extremities of the top side 5, 5 of the loop so that their cam-shaped edges 4, 4 engage the upper extremities of the sides 7, 7 which latter form abutting shoulders against which these cam-shaped edges bear when the attaching loop A is swung downwardly as shown in Figs. 3 and 4. This action of the cam-shaped edges 4, 4 against the abutting shoulders 7, 7 spreads the upper portion of the loop B and draws the pintles 5, 5 apart so that a passage is formed between their extremities 8, 8 the purpose of which will hereinafter appear. The tab C has its extremities d , d attached to the base plate e of the button D by a suitable adhesive substance thereby forming a closed loop, one of the folds of which is passed upwardly from the rear through the opening formed between the ends 8, 8 of the pintles 5, 5. After the closed loop formed in the tab has been passed between the ends 8, 8 of the pintles the attaching loop A is turned upwardly again into the plane of the button loop thereby allowing the top side of the latter to contract and close the passage between the ends 8, 8 of the pintles. The looped extremity of the tab C now embraces the lower side of the attaching loop A and when sufficient tension is placed thereon is supported by the top side of the button loop. In this manner the tab is attached to the clasp after a closed supporting loop has been formed therein. Heretofore it has been necessary to thread the tab around the upper side, or other member of the button loop to which it has been attached, before fastening the extremities of the fabric to form its supporting loop. This, however, would be impracticable in the present instance wherein the extremities are fastened to the button base in the manner above described, since this operation must be performed before the tab is attached to the clasp. It is understood, however, that the supporting loop in the tab may be formed in any other well

known manner since the broad feature of my invention resides in a construction wherein the supporting bar for the tab can be separated between its extremities to form a passage for the supporting loop in the tab during the process of assembling the clasp. It should be observed that the curled pinte straps 3, 3 not only act as a means for spreading the top side of the loop but also serve as journal bearings which engage the outer extremities of the latter, thereby forming a neat pivotal connection which prevents any lateral movement between the two loops when the device is in use. While I have shown the extremities 8, 8 of the pintles 5, 5 as having inclined surfaces, yet it is obvious that these surfaces may be disposed in any other suitable manner. These extremities 8, 8 may be in contact with each other or substantially in contact according to the spring in the wire, the important feature being to close the passage sufficiently so that the fold in the tab can not pass outwardly through the same when the device is in use. While I have shown both the attaching loop and button loop made out of wire, yet it is obvious that either the one or the other may be made out of sheet metal, a particular instance being shown in Figs. 6 and 7 in which the attaching loop F is bent up out of a single piece of wire having its extremities terminating in its lower side forming the inwardly projecting pintles, 9, 9 the extremities of which latter normally meet, or substantially meet. The button loop G, which is made of sheet metal, is provided with a tongue 10 projecting from its upper side 11 which tongue is curled to form a sleeve or bearing for the pintles 9, 9. When the button loop G is blanked the upper side 11, together with the tongue 10, is slit midway and vertically to form the slot 12 which is restricted at its upper extremity but widened as it approaches its lower extremity. The sides of the tongue 10 are tapered to form cam-shaped edges 13, 13 so that when the attaching loop F is turned down as shown these cam-shaped edges bear against the abutting shoulders 14, 14 of the attaching loop and thereby spread the lower side of the latter and draw apart the extremities 15, 15 of the pintles. This spreading action forms a passage between the ends of the pintles which registers or substantially registers with the opening 12 in the journal bearing 10 of the button loop. The supporting loop in the tab is then passed through the passage thus formed and attached to the clasp in the manner hereinbefore described. Referring to the modification shown in Fig. 8, the clasp comprises the attaching loop H and button loop K. The attaching loop H is bent up out of a single piece of wire having its extremities terminating in its lower side 17, 17 and projecting down-

wardly in the form of flattened pinte straps 16, 16. The outside edges of these pinte straps, however, are not formed cam-shaped but are straight. These pinte straps are curled around the outer extremities of the top side of the button loop K so that their outside edges 18, 18 engage the upper extremities of the sides 19, 19, which latter form abutting shoulders against which these straight edges bear, thereby preventing the attaching loop H from becoming distorted or spread when the clasp is subjected to severe strains.

While the devices above described embody the preferred forms of my invention, yet the same are susceptible to such further modification as may fairly come within the scope of the appended claims.

Having now described my invention what I claim and desire to protect by Letters Patent is:

1. A button clasp comprising an attaching loop bent up out of a single piece of wire the extremities of which terminate in downwardly projecting pinte straps spaced apart, one of said straps having a cam-shaped outside edge, and a wire button loop having its top side formed by bending the extremities of the wire inwardly to form pintles the ends of which latter substantially meet; the said pinte straps being curled around the extremities of said pintles so that the said cam-shaped edge will bear against the adjacent side of the button loop and separate the ends of the pintles to form a passage for the looped extremity of a button tab when one of the loops is turned out of the plane of the other.

2. A button clasp comprising an attaching loop having its lower side open and provided with downwardly projecting pinte straps one of which has a cam-shaped outside edge, and a wire button loop having its top side formed by bending the extremities of the wire inwardly to form pintles the ends of which latter substantially meet, the said pinte straps being curled around the extremities of said pintles so that the said cam-shaped edge will bear against the adjacent side of the button loop and separate the ends of the pintles to form a passage for the looped extremity of a button tab when one of the loops is turned out of the plane of the other.

3. A button clasp comprising an attaching loop, a button loop and spaced journal bearings carried by one of said loops and curled around the adjacent side of the other loop, the outside edge of one of said journal bearings being cam-shaped and the said adjacent side being bifurcated between said bearings and provided with shoulders against which bear the outside edges of said bearings, whereby a passage is formed through said adjacent side for the looped extremity of a

button tab when one of the loops is turned out of the plane of the other.

4. A button clasp comprising an attaching loop and a button loop, one of said loops being provided with a cross bar and shoulders at the ends and to one side of said cross bar, the other loop being bent up out of a single piece of wire having its extremities provided

with integral and cylindrical journal bearings, the said bearings being carried by said cross bar and spaced apart so that their outside edges bear against said shoulders. 10

In testimony whereof I have hereunto set my hand this 28th day of June, 1918.

HENRY J. STUART.
